George W. Pittcock & John Pittcock, of Union Mills, N.Y.
Assignors to H. M. Chase, of West Providence.
Letters Patent No. 1126. Dated July 26, 1859.

The schedule referred to in these Letters Patent and making part of the same.

To all whom it may concern:

Be it known that we, George W. Pittcock and John Pittcock, each of Union Mills, in the County of Fulton, and State of New York, have jointly invented or produced a new and original ornamental Design for a Cork Stove; and we do hereby declare that the following is a full and exact description of the same, reference being had to the annexed photographic drawings making a part of this specification, in which -

Fig. 1. represents the front, and

Fig. 2. a side, of the Stove.

Our ornamental design for a cork stove consists of a pair of shells, a, and an ornamental border, b, on each front door; a grooved scroll, c, and a compound molding, d, on each lateral side, and a flower branch, e, e, under each door, of the front plate; a fruit branch, f, on the panel, and an ornamental molding, g, along the border, of the large oven door, and a flower or fruit branch, h, and an ornamental border, i, on the two other doors, or panels, of the side plate; the whole being so formed and arranged as to present the same appearance as is represented in the annexed photographs.

What we claim as our invention or production and desire to secure by Letters Patent is, the ornamental design for a Cork Stove herein described and represented in the annexed photographic drawings.
